UNITED STATES PATENT OFFICE

2,459,087

CHALK HOLDER

George F. Miller, Chicago, Ill.

Application September 17, 1945, Serial No. 616,756

1 Claim. (Cl. 273—20)

1

This invention relates in general to a holder adapted to be suspended for periodic use and is more particularly described as a chalk holder and applicer for billiard cues.

An important object of the invention is to provide a holder for chalk, preferably in rectangular or cubical form as applied to a billiard cue, in which the chalk is easily inserted within the holder and having an opening for applying the chalk to the end of a cue without the chalk coming in direct contact with the hands.

A further object of the invention is to provide an improved simple holder for billiard chalk composed of a pair of flexible elements connected relatively at right angles to each other.

Still a further object of the invention is to provide a simple chalk holder including a suspending means for also holding the chalk in place and having an opposite opening for applying the chalk to the end of a cue.

A further object of the invention is to provide a simple chalk holder for cues and the like, comprising a pair of members connected together relatively at right angles to each other by simple fastening means such as rivets or staples and completely covering the chalk.

Further objects of the invention will appear in the specification and will be apparent from the accompanying drawings in which:

Fig. 1 is a side elevation of the chalk holder constructed in accordance with the principles of this invention;

Fig. 2 is another side elevation of the holder shown in Fig. 1 and at right angles thereto;

Fig. 3 is a view of the lower, or applying end of the holder;

Fig. 4 is a sectional view taken on the line 4—4 of Fig. 1; and

Fig. 5 is a sectional view taken on the line 5—5 of Fig. 4.

Billiard cue chalk is now commonly made in cubical or rectangular form which requires a particular form of holder to hold closely the chalk, to provide means for readily inserting and removing chalk from the holder, and to apply the chalk in the holder to the end of a cue without soiling the hands of the user or allowing them to come in direct contact with the chalk.

The present invention accomplishes these results by providing a two piece holder composed of flat strips secured together, it being unnecessary to press either of the strips to any special form or shape, and the holder thus provided accurately fitting the chalk and providing means

for suspending the holder by means of a cord or spring where the holder and the chalk are readily accessible.

Referring now more particularly to the drawings, a cubical or rectangular piece of chalk 10 is now commonly manufactured and used for applying the chalk to the end of a billiard cue. This chalk receives a rounded depression 11 in one face by its application to the end of a cue and the chalk is used up by a continuance of such application to the end of the cue.

The present holder is particularly designed and intended for receiving and applying chalk of this shape and comprises a pair of strips 12 and 13 of flexible material such as leather, fabric, plastic and the like, the two strips being suitably fastened together by rivets or staples 14 and 15 at opposite sides of the holder.

One of the strips 12 is substantially of the same height or thickness as a piece of chalk and of a length to extend closely around the chalk with the ends overlapping at one side thereof. The other strip 13 is slightly wider and preferably of a width to receive a piece of chalk and the opposite sides of the strip 12 therein so that the strip 13 may be applied at right angles around the strip 12 in its folded position to enclose a piece of chalk therein, an intermediate portion of the strip 13 having an opening 16 preferably circular, so disposed that it will be at one end of the strip 12 in its folded position or at the bottom of the chalk opposite a depression 11 which is made therein. The opposite ends 17 and 18 of the strip 13 are folded together at the upper or opposite side of the holder, the extremities being provided with openings 19 which register with each other and provide means for the attachment of a cord or string 20 therethrough by means of which the holder and the chalk therein may be suspended. The ends 17 and 18 extend angularly upward toward each other and from the inner strip 12 since it is not important that these portions of the holder fit tightly against the chalk.

In applying chalk to the holder, the ends 17 and 18 are spread apart, the chalk is inserted within the inner member 12 of the holder and the ends 17 and 18 are fastened together by a string or cord 20 which prevents the chalk from being accidentally dislodged or lost from the holder.

To apply the chalk in the holder to the end of the cue, the holder is grasped with one hand and the parts 12 and 13 are of sufficient resilience that the chalk can be held or retained in fixed

position therein, the end of the cue being inserted through the opening 16 at the bottom of the holder and in contact with the chalk as desired. In accomplishing this chalking action, the hands do not come in contact with the chalk and the particles of chalk may be dislodged from the holder, thereby making it unnecessary to remove the chalk from the hands after each operation.

The use of this holder prevents the chalk from being lost or displaced thereby resulting in an economical use of the chalk, and the chalk itself lasts much longer because particles are not easily broken therefrom by dropping the chalk, and by attaching the holder in a specified place by means of a string or cord, the chalk is always easily located thereby saving considerable time in its use and application.

While the preferred use and application of this holder is here shown and described, various changes in the construction, combination and arrangement of the parts may be made without departing from the spirit and scope of the invention.

I claim:

A holder for a cubical piece of billiard cue chalk having a single face engaged by the end of the cue, comprising two separate flexible strips each substantially the width of one of the chalk sides,

one strip being of a length to extend entirely around the chalk but not over the engageable face and the ends overlapping on one face, the other strip having a single cue end opening intermediate its ends to register with the engageable face and of a length to extend around the chalk at right angles to the first strip with the ends extending together outwardly opposite the cue opening and with perforations in the ends adapting the holder to be suspended by a supporting cord engaging therein, and fastening means connecting the two strips together at opposite sides of the chalk where these strips cross, and the chalk being insertable in the holder by spreading apart the perforated ends of the suspending strip at the side of the holder opposite the single cue opening.
